UNITED STATES PATENT OFFICE.

ALICE LYELL MANN, OF NEW YORK, N. Y.

GARMENT-HANGER.

Specification of Letters Patent. Patented Dec. 9, 1913.

1,080,767.

Application filed March 15, 1913. Serial No. 754,480.

To all whom it may concern:

Be it known that I, ALICE LYELL MANN, a citizen of the United States, residing at New York, in the county of New York and State of New York, have invented new and useful Improvements in Garment-Hangers, of which the following is a specification.

My invention relates to improvements in garment hangers, and has for its chief object the provision of a simple garment hanger which may be collapsed or folded into compact form so that it may be conveniently carried in the trunk or valise of a traveler, and which is adaptable for the neat 10 and convenient disposition of garments in hotels and other places lacking any convenient and commodious facilities therefor.

With this object in view, the invention 20 consists in the novel garment hanger hereinafter described and claimed, reference being had to the accompanying drawing for illustration thereof.

In said drawing,—Figure 1 is a plan view illustrating a number of the improved garment hangers arranged for use upon a garment hanger support. Fig. 2 is a plan view of the garment hanger of my invention with a plain bar such as is suitable for the support of a princess dress. Fig. 3 is a similar 30 view of such a hanger with a support having hooks for the reception of the loops of a skirt, and showing in dotted lines the mode of operation of removing the support-engaging hook thereof preparatory to folding the hanger into compact form for carrying in a 35 trunk or valise. Fig. 4 is a view showing the hanger folded in compact form for convenience for carrying in a trunk or valise or suit-case. Fig. 5 is a detail perspective view 40 illustrating the manner of assembling the garment support hook into the composition of the hanger.

In the said drawing, I have illustrated several different forms of garment hangers 45 as illustrative of the invention, which invention is present in each form and may be in other particular forms adapted for the support of particular garments.

In the said drawing, the reference number 50 1 designates the garment support; that is to say, that part of the hanger which directly receives the garment for the support thereof. In Fig. 2 of the drawing this support is in the form of a plain cylinder suitable for supporting, for instance, a prin-

cess dress in folded condition thereon. In Fig. 3 this support is a bar or rod provided with hooks 2 suitable to receive the loops of a skirt to be hung pendent therefrom, and in Fig. 6 the support consists of the usual 60 form of a coat hanger.

Referring now to Figs. 2 and 3 of the drawing the numerals 3 designate arms which may be conveniently constructed of wire hinged or pivoted to the rod 1, for 65 example by means of inter-engaging eyes 4 of the rods 3, and 5 of screw eyes or bolts 6 carried by the rod 1. The free ends of the arms 3, which are brought into register when in use for the reception of the 70 hanger support hook 7, are bent angularly, as at 8, so that the eyes 9 at the extremities of said arms may be brought into parallelism and registration so that the hook 7 may be readily assembled in the structure by being 75 passed through the registering eyes, as illustrated in Fig. 5 and made to assume the operative position illustrated, for example, in Fig. 2. It will thus appear that the said hook is readily insertible into the structure 80 and may be easily manipulated to permit the arms 3 to move upon the hinge connection with the bar 1 to assume the folded position shown in Fig. 4. The stem of the hook 7 is provided with an enlargement or button 10 85 as an abutment for the eyes 9 of the arms 3, so that the said arms and the bar 1 are properly suspended from the hook when the latter is connected with a garment hook support, and the registering eyes 9 form what, 90 for convenience, I term a hook rider; that is to say, the walls of the two eyes 9 disposed in parallelism present, combined, a wall of such narrowness that the hook may be assembled into the structure by passing 95 the free end of the hook through the eyes, as illustrated in Fig. 5, the curved portion of the hook freely passing through the eyes by a swinging movement, which will be 100 readily understood by reference to said figure of the drawing, the straight or stem portion of the hook following along until the hook assumes the position shown in Fig. 2; and the hook may be separated by a reverse mode of operation, as illustrated in 105 Fig. 3 of the drawing.

In disposing the parts of the hanger in the folded condition illustrated in Fig. 4, it is not necessary that the hook shall be entirely separated from both arms, but may be 110

left with its hook end in engagement with the eye of one of the arms. This is shown in Fig. 4 of the drawing.

From the foregoing description, it is obvious that the hanger is a foldable one which may be made to assume the compact form illustrated in Fig. 4 convenient for carriage by the traveler, and that the hook portion may be readily assembled in the construction without the manipulation of nuts or like contrivances, but by a mere passing of the hook through the hook rider eye, the curvilinear or hook end riding upon the walls of said eye, and, finally, that when assembled the hook is swiveled in the eyes so that the garment support 1 and the arms 3 of Figs. 2 and 3 may be turned to different angular positions with relation to the hook stem. This is of material advantage. In many cases hotels and other places of sojourn are not provided with adequate facilities for disposing one's garments. Very often the closets or wardrobes are shallow or very little in depth so that garment hangers cannot be received therein supported by a hanger support in parallel relation; that is to say, the depth is not sufficient to accommodate the length of the supporting bar of the hanger or the length of a coat hanger, and this is a serious difficulty. By providing the swivel connection of the hook with the garment supporting portion of the hanger the latter may be turned to different angular positions with relation to the hook, so that the ideal parallel relation of the hangers which cannot be obtained in such circumstances may be as near as possible ap-

proximated. This is illustrated in Fig. 1 of the drawing.

In practice, for economy of space, and this is very desirable because of the inadequacy of facilities for the proper disposition of garments in many hotels, it is designed that an equipment for garment hangers shall have hooks the stems of which are of different length, as shown in Fig. 1, so that when the hangers are supported, as shown in Fig. 1, they may be arranged in close relation, the garment supporting bars or members thereof being in different horizontal planes so that there will be no bunching or crowding of the garments as would be the case if the bars were arranged all on the same plane, as will be obvious.

Having thus described my invention, what I claim is:—

A garment hanger comprising a garment support, arms pivotally connected therewith to be foldable thereagainst, said arms provided with horizontal free extremities having registering eyes, and a hanger hook with a stem having swivel connection with said eyes, the curved end of said hanger hook being adapted to be passed through said eyes for assembly and disassembly of the hanger.

In testimony whereof I have hereunto set my hand in presence of two subscribing witnesses.

ALICE LYELL MANN.
